No. 37,192.

Patented October 25, 1904.

UNITED STATES PATENT OFFICE.

OTTO SCHOTT, OF JENA, GERMANY, ASSIGNOR TO SCHOTT & GEN, OF JENA, GERMANY, A FIRM.

DESIGN FOR A LAMP-GLASS.

SPECIFICATION forming part of Design No. 37,192, dated October 25, 1904.

Application filed August 10, 1904. Serial No. 220,274. Term of patent 7 years.

To all whom it may concern:

Be it known that I, OTTO SCHOTT, a citizen of the German Empire, residing at 5 Lichtenhainerstrasse, Jena, in the Grand Duchy of 5 Saxe-Weimar, German Empire, have invented a new, original, and ornamental Design for Lamp-Glasses, of which the following is a specification, reference being had to the accompanying drawing, forming part thereof.

10 The figure is a perspective view of a lamp-glass, showing my new design.

What I claim as new, and desire to secure by Letters Patent, is—

The ornamental design for a lamp-glass, as herein shown.

OTTO SCHOTT.
